UNITED STATES PATENT OFFICE.

STARK W. CRADDOCK, OF RICHLAND, MISSOURI.

PERMUTATION LOCK.

1,418,778.

Specification of Letters Patent. Patented June 6, 1922.

Application filed May 6, 1921. Serial No. 467,321.

To all whom it may concern:

Be it known that I, STARK W. CRADDOCK, a citizen of the United States, residing at Richland, in the county of Plaski and State 5 of Missouri, have invented certain new and useful Improvements in Permutation Locks, of which the following is a specification.

This invention relates generally to permutation locks for securing the doors of steel 10 safes and vaults against being opened by unauthorized persons and has for its principal object to arrange the parts of the mechanism in such a manner that no jar, click, or noise whatever can be heard or 15 felt during the operation of the tumbler disks thereby preventing persons relying on sensitive fingers or sounds from ascertaining the combination and opening the lock.

Another object of the invention is to 20 generally improve upon locks of this character by providing a device which will be of extremely simple, durable and inexpensive construction, one which may be easily assembled and disassembled and is 25 efficient and reliable in operation, and well adapted to the purpose for which it is designed.

With these and numerous other objects in view, the invention resides in certain novel 30 features of construction, and the combination and arrangement of parts as will be hereinafter fully described and claimed.

In the drawing:

Figure 1 is an elevational view of the 35 lock showing same as used with the bolting mechanism,

Figure 2 is a front elevation of the lock,

Figure 3 is a rear elevation thereof,

Figure 4 is a vertical section taken through 40 the lock,

Figure 5 is a rear elevational view of a block used with the lock,

Figure 6 is an end elevation thereof,

Figure 7 is a section taken therethrough, 45 on line 7—7 of Figure 5,

Figure 8 is an edge elevational view of the bolt operating mechanism parts thereof being shown in section,

Figure 9 is a perspective view of the 50 sliding block used in connection with the latch,

Figures 10, 11, 12, 13 and 14 are plan views of the tumbler disks,

Figure 15 is a plan view of the washer,

Figure 16 is a plan view of the end disk 55 for enclosing the tumbler disks,

Figure 17 is a plan view of the permutation changing means,

Figure 18 is a plan of the flange 46, and

Figure 19 is a section taken on the line 60 19—19 of Figure 17.

Referring to the drawings in detail it will be seen that 1 designates the horizontally disposed locking bolts which are usually found on a safe door and are connected by the vertical strip 2. A link 3 connects the strip 2 with the bolt 4 which extends through the casing 5 of the lock adjacent its upper end and is provided with an opening 6 extending vertically therethrough as is shown in Figure 4. This bolt 4 is also provided with a pair of stop pins 7 so as to limit its transverse sliding movement.

The bolt operating mechanism 8 includes 75 the semi-circular body 9 having a radially extending finger 10 which is positioned in the opening 6. This bolt operating mechanism is mounted on suitable bearings 8' and rotated by the square shaft 11 which extends 80 through the semi-circular member 9 and is provided at one end with an operating handle 12 so that the same may be rotated. The screw 13 or other suitable means holds 85 the shaft 11 in detachable engagement with the member 9. Upon rotation of the body 9 by the handle 12 through the intermediacy of the shaft 11 the finger 10 may be moved so as to slide the bolt 4 and thereby actuate the bolts 1 through the intermediacy of the 90 link 3 and strip 2. An apertured bracket 14 is mounted in the casing 5 a distance from the shaft 11 and is adapted to pivot in the casing. This bracket 14 slidably receives in its aperture the rod 15 which is pivotally 95 connected to the body 9 at 16. A spring 18 is disposed between the bracket 14 and the pivot point 16 and is suitably fixed to the rod 15 at 19 so that when the finger 10 is in a vertical position the spring 18 will be compressed whereas when the finger 10 is in the position shown in Figure 4 the spring 14 will be extended and tend to hold the body 9 in this position.

Should the body 9 be rotated, in Figure 4, in a clockwise direction so as to place the bolt in an unlocking position this spring 18 will tend to hold the bolt 4 in its unlocked position through 100 105

the intermediacy of the bolt operating mechanism 8 as will be evident from an inspection of the drawings.

The body 9 is provided with a notch 20 at its lower end in which is slidably mounted a latch block 21 which is shown to advantage in Figure 9. A longitudinally extending cylindrical bore 22 communicates with the notch 20 so as to receive the shank 23 of the latch block 21 and as indicated in Figure 4 there is a coil spring mounted thereon which will bear against the end of this shank 23 so as to normally hold the lower end of the latch block 21 in alignment 10 with the curved periphery of the body 9. In order to limit the sliding movement of the block 21 and its shank 23, this shank is provided with a longitudinally extending slot 24 which receives the pin 25 carried 15 in the block 21. On the one face of the block 21 there is provided a projection 26 having a vertical slot 27 therein. This projection is slideable in the groove 28 in the vertical wall of the notch 20 and a pin 20 extends transversely of this groove 28 and passes through the slot 27 as shown at 29 in Figure 4. The body 9 of the bolt operating mechanism 8 is provided with a circular groove 30 on each side which is preferably 25 concentric with its curved periphery. These grooves 30 may be of any length but it is preferable to have them of approximately ninety-five degrees. The grooves 31 on the side faces of the latch block 21 normally register with the grooves 30 that is when the pin 25 is in abutment with the upper end of the slot 24. The grooves 31 are concentric with the lower face 32 of the latch block 21 and it will be noted that this lower face 30 is beveled upwardly toward the side opposite that upon which is mounted the projection 26.

The latch mechanism just described is operated and controlled by a permutation mechanism later to be described through the intermediacy of the lever 33 which is pivotally mounted in a groove on the upper side of a block 34 which is positioned in the body of the casing 5. The construction of this lever 33 is best shown in Figures 5 and 6 wherein it will be seen that a depending tongue 34 extends from the under face of the lever adjacent its free end while a pair of arms 35 extend upwardly from the upper face of the lever and are spaced from each other and provided with the inwardly extending and aligning lugs 36 which are adapted to ride in the grooves 31 and 30 upon rotation of the bolt 60 operating mechanism 8. On the lower edge adjacent one end of the tongue 34 there is provided a lug 37 which is indicated in dotted lines in Figure 6.

The permutation mechanism about to be 65 described is similar to that disclosed in my

pending application for a permutation lock Serial Number 435,400 filed January 6, 1921. The knob 38 is provided with the usual indices as indicated in Figure 2 and is mounted on or made part of the shank 39 which 70 is provided with a reduced extension indicated by the dotted lines in Figure 7 at 40. This reduced stem extends through the block 34 so as to be centrally located in the cylindrical recess 41. The rear portion of this 75 recess 41 is open while the other end thereof is closed as is shown at 43 except for the opening through which a reduced portion 44 of the shank 39 is rotatably mounted. Channels 45 are disposed in the recess 41 and 80 are preferably diametrically disposed in relation to each other.

A sleeve 42 is mounted on the stem 40 so as to be capable of rotation independently thereof and is provided upon its outer end with a flange 46 which is provided with a plurality of apertures. A locking disk 47 is suitably keyed to the end of the stem 40 and held in engagement therewith by a screw 48. This disk 47 is provided with a 90 plurality of circumferentially arranged apertures which are adapted to be registered with the apertures provided in the flange 46 so that this disk 47 may be suitably locked to the disk 46 by means of the screw 49 and 95 thus the combination of the permutation mechanism may be changed when desired as will appear as the description progresses.

The sleeve 42 will be first positioned in its proper place in the recess 41. The tumbler disk E, shown in Figure 10, is provided with the central circular opening 51 and the rib engaging groove 52 in communication therewith so that this disk E may be positioned as shown in Figure 7, that is so that the 100 sleeve 42 is mounted in the opening 51 while the groove 52 is disposed so as to receive the rib 50 of sleeve 42. The washer G is now 105 positioned in place and this washer, see Figure 15, consists of a body portion having a segment thereof removed and is provided with an enlarged central opening 53 and the diametrically opposed apertured ears 54 which are received by the bolts 55 mounted in the channels 45 and in the forward portion 110 of the block 34. The remaining tumbler disks D, C, B, and A are placed in position in the order named having mounted therebetween a washer G and it will be noted that each of the disks E, D, C, B, and A are 115 provided with the central circular opening 51 and the rib engaging groove 52. The washers G are spaced from each other by means of the spacing sleeves 56 mounted on the bolts 55. It will be noted that the size 120 of the groove 52 in the disks A to E gradually decreases in the order mentioned. The closure disk F is provided with the circular 125 centrally located opening 57 and the diametrically opposed apertured ears 58 en- 130

gaged by the bolts 55. The end of the sleeve 42 will be received in the opening 57 and it will be noted that a groove 59 is provided in order that the sleeve 42 may be placed on the stem 40 the rib 50 riding in the groove 59. After the closure disk 57 has been placed in position the bolts 55 will be passed through the apertures in ears 54 and 58 and through spacing sleeves 56. The sleeve 42 may now be placed in position and the flange 46 thereof will be keyed to the stem 40 through the intermediary of the disk 47 as has already been explained. It will be noted that each of the tumbler disks is provided with a peripheral notch 60 which when aligned with each other are adapted to receive the tongue 34 of the lever 33. The innermost disk E is provided with a plurality of shallow peripheral notches 61 suitably spaced from each other which are adapted to receive the lug 37 on tongue 34.

The operation of the device should now be understood. The object to be obtained when it is desired to open the lock is to move the tumbler disks A to E so that the peripheral notches 60 will be in alignment with each other and with the tongue 34, it being understood that the tongue 34 is adapted to penetrate through the block 34' into the recess 41 when the lever 33 is pushed downwardly. This aligning of the peripheral notches 60 is accomplished through rotation of the knob 38 back and forth placing the necessary indices thereon in alignment with the mark sixty five on the casing 5. Supposing for example that the combination is zero, eighty seven, twenty one, sixty two and thirty nine. The knob 38 will now be rotated in a clockwise direction for at least one full turn and then continued until the index zero is in alignment with the mark sixty five. This operation will cause the rib 50 to engage one end of the groove 52 in the tumbler disk A so as to place its peripheral notch 60 in alignment with the tongue 34. The knob 38 will now be rotated in a counter-clockwise direction until the index eighty seven aligns with the mark 65 and this movement will cause the rib 50 to engage the end of the groove 52 in tumbler disk B thereby aligning its peripheral notch 60 with the tongue 34 and in thus rotating the knob 38 it will be noted that the disk A will not have moved since its groove 52 is greater than the groove 52 in tumbler disk C. The knob 38 will now be rotated in a clockwise direction so as to place the index twenty one in alignment with the mark sixty five and in this movement the peripheral notch 60 will be placed in alignment with the tongue 34 in a manner similar to that set forth in connection with tumbler disks A and B. The knob 38 will now be rotated in a counter-clockwise direction so as to place the index sixty two in alignment with the mark sixty five

thereby placing the peripheral notch 60 of the disk D in alignment with the tongue 34. The knob 38 will now be rotated in a clockwise direction so that the index thirty nine on the knob 38 registers with the mark 65 70 which will place the peripheral notch 60 of the disk E in alignment with the tongue. At this time it will be easily understood that by changing the position of the disk 47 in relation to the flange 46 the combination may 75 be changed from time to time as may be desired.

When the peripheral notches 60 are all in alignment with the tongue 34 it will be seen that by rotating the handle 12 in a counter clockwise direction the bolt operating mechanism may be rotated at which time the pins 36 on the arms 35 on the lever 33 will ride in the grooves 31 of the latch block 21 and into the groove 30 on the body 9. 85 If however, the peripheral notches 60 were not in alignment with the tongue 34 it will be noted that upon rotation of the bolt operating mechanism 8 the latch block 21 would be forced inwardly and the tongue or arm, end of the lever 33 would abut against the face of the notch 20 provided with the groove 28 and prevent further rotation of the bolt operating mechanism. In this slight rotation of the bolt operating mechanism it will be noted that the bolt 4 would not be moved since the opening 6 is large enough to allow a slight movement of the finger 10 therein.

As is well known unauthorized persons 100 desiring to operate a lock mechanism of the nature now under consideration, usually turn the handle 38 slightly so that they may hear the click of the tumbler disks as they are rotated. In order to prevent this I have 105 provided the disk E with a plurality of peripheral notches 61 so that as the knob 12 is turned the grooves 31 in the lock block 21 because of their slanting position will tend to bear upon the pins 36 thus pushing 110 downwardly upon the lever 33 and causing the lug 37 to engage one of the shallow peripheral notches 61 and prevent further rotation of the knob 38 and thus the only possible click which the unauthorized person 115 might hear or feel would be that occasioned by the lug 37 engaging the peripheral notches 61 and 60 of the disk E which would in no way aid him in discovering the proper combination.

From the foregoing description, taken in connection with the accompanying drawings, the advantages of the construction and the method of operation will be readily apparent to those skilled in the art to which the 125 invention appertains and while I have described the principle of operation of the invention together with the device which I now consider to be the best embodiment thereof, I desire to have it understood that 130

the device shown is merely illustrative and that such changes may be made as are within the scope of the claimed invention.

Having thus described my invention what I claim as new is:—

1. In combination, a bolt, a bolt operating mechanism therefor, said mechanism including a body provided with a semi-circular groove, means for rotating the body, a block slidably mounted in relation to the bolt operating mechanism and carried thereby provided with a groove normally adapted to register with the groove in the body of the latch mechanism, an element for preventing the rotation of the body normally positioned in the groove of the block and slidably in both of said grooves, means provided for moving the block so as to place its groove out of alignment with the groove in the body thereby preventing rotation of the body in the manner and for the purpose specified.
2. In combination, a bolt, an operating mechanism therefor, including a body provided with a groove, a block slidably mounted in the body and provided with a groove adapted to normally register with the groove of the body, means for resiliently holding said block so that its groove will register with the groove in the body, a lever pivotally mounted and provided with an element slidably in both of said grooves but normally positioned within the groove of the block, and means for controlling the lever so as to place said grooves in or out of alignment with each other so as to allow or prevent the rotation of said body.
3. In combination, a bolt, an operating mechanism therefor including a rotatable body, means for rotating the body, said body

provided with a groove, a member slidably mounted on the body and provided with a groove, means provided for normally holding the groove in the member in alignment with the groove in the body, a lever provided with an element slidable in the grooves, a tongue projecting from the lever, a permutation mechanism comprising a plurality of tumbler disks provided with peripheral notches, the edge of said tongue adapted to terminate adjacent the periphery of the tumbler disks so as to normally prevent the movement of said lever, and means for rotating the tumbler disks so as to place the peripheral notches thereof in alignment with the tongue so as to allow movement of the lever and rotation of the bolt operating mechanism.

4. In combination, a bolt, an operating mechanism therefor including a rotatable body, said body provided with a notch and a groove communicating therewith, a block slidably mounted in said notch and provided with a groove, means for normally holding the block in such a position that its groove will register with the groove of the body, an element slidable in said groove, and means controlling said element so that the groove of the block may be placed out of alignment with the groove in the body thereby preventing the operation of the bolt operating mechanism.

In testimony whereof I affix my signature in presence of two witnesses.

STARK W. CRADDOCK.
